US00D388134S

United States Patent [19]

Dunipace

[11] Patent Number: Des. 388,134

[45] Date of Patent: **Dec. 23, 1997

[54] FLYING DISC

[75] Inventor: David Bruce Dunipace, Fontana, Calif.

[73] Assignee: Innova Champion Discs, Inc., Rancho Cucamonga, Calif.

[**] Term: 14 Years

[21] Appl. No.: 50,858

[22] Filed: Feb. 28, 1996

Related U.S. Application Data

[60] Continuation of Ser. No. 44,179, Sep. 19, 1995, abandoned, which is a division of Ser. No. 18,864, Feb. 16, 1994, Pat. No. Des. 369,191.

[51] LOC (6) Cl. 21-01

[52] U.S. Cl. D21/86; D21/82

[58] Field of Search D21/82, 86; 446/46, 446/48; 473/569, 588, 589
